No. 888,079.

PATENTED MAY 19, 1908.

T. H. FURMAN.
TOOL CHEST HANDLE.
APPLICATION FILED SEPT. 11, 1907.

UNITED STATES PATENT OFFICE.

THOMAS H. FURMAN, OF SEWARD, DISTRICT OF ALASKA.

TOOL-CHEST HANDLE.

No. 888,079.

Specification of Letters Patent.

Patented May 19, 1908.

Application filed September 11, 1907. Serial No. 392,368.

To all whom it may concern:

Be it known that I, THOMAS H. FURMAN, a citizen of the United States, residing at Seward, in the District of Alaska, have invented certain new and useful Improvements in Tool-Chest Handles, of which the following is a specification.

The present invention relates to certain new and useful improvements in that type 10 of handles which are commonly employed in connection with tool chests and the like, and aims to provide a novel form of handle which is peculiarly designed so as to retain itself in such a position as to be protected 15 from injury when not in use.

A further object of the invention is to provide a handle of this character which is of simple and durable construction and can be readily applied to a tool chest or like member.

For a full understanding of the invention and the merits thereof and also to acquire a knowledge of the details of construction and the means for effecting the result, reference 25 is to be had to the following description and accompanying drawings, in which:

Figure 1 is a perspective view showing the device applied. Fig. 2 is a front elevation of the improved handle. Fig. 3 is a longitudinal sectional view through the handle.

Corresponding and like parts are referred to in the following description and indicated in all the views of the drawings by the same reference characters.

Specifically describing the present embodiment of the invention the numeral 1 designates the base plate which is designed to be secured in position upon a tool chest or the like by any suitable means such as the 35 bolts 2. A recess 3 is formed in the outer face of the base plate 1 and opposite sides of the said recess are connected by a rod 4 which is preferably located toward the upper 40 end of the base plate and is disposed approximately parallel to the base of the recess.

It will be observed that a depression 5 is formed in the base of the recess 3 immediately under the rod 4. The handle 6 is normally housed within the recess 3 and comprises a pair of arms which are pivotally mounted upon the rod 4, the extremities of 50 the arms being rounded and operating within the depression 5. When it is desired to

use the handle 6 the same is swung outwardly at an angle to the base plate 1, and the swinging movement of the said handle is limited by shoulders 7 upon the rounded ends of the arms of the same, said shoulders being designed to engage the base of the recess 3.

For the purpose of holding the handle 6 normally within the recess 3 where it is protected from injury a coil spring 8 is employed and surrounds the rod 4, one end of the spring being bent laterally and having its extremity embedded in one of the arms of the handle 65 while the opposite end engages the base plate 1. Notches 9 are formed in the lower portion of the handle and enable the fingers of the operator to readily obtain a hold thereon when moving the handle into an operative 70 position.

It will be readily apparent from the foregoing description that when not in use the handle is held within the recess and housed thereby regardless of the position of the box 75 or member to which the handle is applied.

Having thus described the invention, what is claimed as new is:

1. In a handle, the combination of a base, a rod carried by the base, the said base being 80 formed with an auxiliary depression immediately under the rod, a handle comprising arms pivotally mounted upon the rod and having the extremities thereof rounded and received within the before mentioned depression, and a spring holding the handle yielding 85 against the base.

2. In a handle, the combination of a base having a depression therein, a rod carried by the base and disposed over the depression, a 90 handle comprising arms pivotally mounted upon the rod, the ends of the arms being rounded and received within the before mentioned depression in the base, the said rounded ends being provided with shoulders for 95 engaging the base to limit the swinging movement of the handle, and a spring arranged upon the rod and normally holding the handle against the base.

In testimony whereof I affix my signature 100 in presence of two witnesses.

THOMAS H. FURMAN. [L. s.]

Witnesses:

S. O. MORFORD,
CURTIS R. MORFORD.
